UNITED STATES PATENT OFFICE.

WILLIAM GOULD BROKAW, OF PARIS, FRANCE.

APPARATUS FOR INFLATING LIFE-PRESERVING BELTS.

1,230,858.

Specification of Letters Patent. Patented June 26, 1917.

Application filed April 27, 1917. Serial No. 164,897.

To all whom it may concern:

Be it known that I, WILLIAM GOULD BROKAW, a citizen of the United States of America, residing at Paris, France, have invented Improvements in Apparatus for Inflating Life-Preserving Belts, of which the following is a specification.

This invention relates to apparatus for inflating life-preserving belts described in the specification of my British application for Letters Patent No. 103790 dated September 29th, 1916.

The said apparatus comprises a member arranged to operate a valve whereby gas for inflating the belt is released from a cartridge located within the belt, a diaphragm being interposed between the cartridge valve and the operating member which is located at the exterior of the belt.

The object of the present invention is to provide apparatus of the said kind in which the valve for releasing the gas from the cartridge is actuated by a more direct axial thrust than is the case with the apparatus described in the specification of my said former application thereby rendering the opening of the valve more certain and insuring the release of the gas and consequent inflation of the belt when the operating lever is moved in the manner necessary to produce this effect.

For this purpose, according to the invention the gas cartridge valve is operated by pressure on a plate arranged at the outer side of the diaphragm located between the valve and the operating member, the said plate bearing against a fixed pin or the like that constitutes a fulcrum about which the plate turns when pressed inwardly to open the cartridge valve.

In the accompanying illustrative drawings Figure 1 is a front elevation of valve operating mechanism embodying the invention.

Fig. 2 shows the mechanism partly in elevation and partly in section corresponding to the line A A of Fig. 1.

Fig. 3 shows the mechanism partly in plan and partly in horizontal section corresponding to the line B B of Fig. 2.

Fig. 4 is a rear view of the mechanism with the cartridge and valve removed, and,

Fig. 5 is a front view of the diaphragm showing the pressure plate.

a indicates a part of the wall of the inflatable belt which may be of any usual kind

and b is the cartridge screwed into a connector c which is in turn screwed into the hub of the dished disk d between which and an outer shell e the diaphragm f is clamped. 60 g is a tightening ring fitted inside the belt a and from which project studs h whereby the several parts are secured together and to the belt as described in my said British specification. 65

Fixed to the inner side of the diaphragm f is a valve operating pin k and at the outer side of the diaphragm is a pressure plate m adapted to bear as shown against a fulcrum pin n fixed to the shell e. Mounted to turn 70 on a pin o carried by the shell e is an operating lever one arm p of which is located within the shell and adapted to bear on the plate m to open the valve, and the other arm r of which extends through a slot formed in 75 the shell and terminates in a finger piece.

Assuming the apparatus with loaded cartridge b applied to a belt worn on the person, upon turning the lever p, r about its 80 its pivot o the arm p thereof will bear on the plate m and cause such plate to move inwardly about the fixed fulcrum pin n thereby through the pin k, operate the valve located within the hub of the disk d in such way as to release the gas from the cartridge 85 b and cause the inflation of the belt. As will be seen the construction is such that the pressure on the valve to open it is a direct thrust in the line of the valve axis and consequently the valve is opened with certainty 90 at each operation.

What I claim is:—

1. In apparatus for inflating life-preserving belts, a gas cartridge, a holder for said cartridge secured to the wall of an inflatable life belt, a gas release valve carried by said holder, a diaphragm fixed to said holder, a pin on the inner side of said diaphragm adapted to actuate said valve, a plate at the outer side of said diaphragm, a 100 fulcrum for said plate fixed to said holder, an operating lever mounted in said holder adapted to turn said plate about said fulcrum in a direction to move said diaphragm inwardly and operate said valve. 105

2. In apparatus for inflating life-preserving belts, a dished disk secured to the wall of an inflatable belt, a gas cartridge located within the belt and carried by said disk, a valve mounted in said disk and 110 adapted to control the escape of gas from said cartridge, an outer cover fixed to said

disk, a diaphragm the margin of which is clamped between said disk and said cover, a pin on the inner side of said diaphragm adapted to actuate said valve, a plate on the outer side of said diaphragm, a fulcrum on said cover against which said plate can bear, and a lever mounted in said cover adapted to turn said plate about said fulcrum in a direction to move said diaphragm 10 inwardly and operate said valve.

3. In apparatus for inflating life-preserving belts, a dished disk secured to the wall of an inflatable belt, a gas cartridge located within the belt and carried by said 15 disk, a valve mounted in said disk and adapted to control the escape of gas from said cartridge, a slotted cover fixed to said disk, a diaphragm the margin of which is clamped between said disk and said cover, 20 a pin on the inner side of said diaphragm adapted to actuate said valve, a plate on the outer side of said diaphragm, a fulcrum on said cover against which said plate can bear, and a lever pivoted to said cover and 25 extending through the slot thereof, the inner end of said lever being adapted to bear on said plate and turn it about said fulcrum to move said diaphragm with said pin inwardly to actuate said valve.

30 4. In apparatus for inflating life-pre-

serving belts, a ring secured to the inner side of the wall of an inflatable belt, a dished disk secured to the outer side of the wall of an inflatable belt, means for securing said disk to said ring to clamp the adjacent portion of the belt wall between them, a gas cartridge located within the belt and carried by said disk, a valve mounted in said disk and adapted to control the escape of gas from said cartridge, a slotted 35 cover fixed to said disk, a diaphragm the margin of which is clamped between said disk and said cover, a pin on the inner side of said diaphragm adapted to actuate said valve, a plate on the outer side of said diaphragm, a fulcrum on said cover against which said plate can bear and a lever pivoted to said cover and extending through the slot thereof, the inner end of said lever being adapted to bear on said plate and 40 turn it about said fulcrum to move said diaphragm with said pin inwardly to actuate said valve.

Signed at American consulate at Nice France this 29th day of March 1917.

WILLIAM GOULD BROKAW.
